(57) **CLAIM**

The ornamental design for a surveillance camera for an automobile, as shown and described.

DESCRIPTION

FIG. 1 is a front and top perspective view of a surveillance camera for an automobile showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and

FIG. 8 is a rear and top perspective view thereof;

FIG. 9 is a front and bottom perspective view thereof; and, FIG. 10 is a partial cross-sectional view thereof taken along line 10-10 in FIG. 6.

The broken lines depict portions of a surveillance camera for an automobile in which the design is embodied that form no part of the claimed design.
